(57) CLAIM

The ornamental design for a lighter as shown and described.

DESCRIPTION

FIG. 1 is a perspective view of a lighter showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an enlarged view of an indicated portion of FIG. 3.

The unshaded surfaces between solid and broken lines form no part of the claimed design. The dash-dash broken lines immediately adjacent shaded surfaces represent bounds of the claimed design and form no part of the claimed design; all other dash-dash broken lines illustrate portions of the lighter that form no part thereof. The dot-dash-dot broken lines rendered in FIGS. 3 and 8 define the enlarged portions and form no part thereof.
